DART GAMES

Augustus M. Henry, Levittown, N. Y.

Application April 28, 1953, Serial No. 351,642

3 Claims. (Cl. 273—102.1)

This invention relates to game apparatus, and more particularly aims to provide new and useful improvements in game apparatus of a kind having the popular appeal of a contest of skill in which a contender attempts to direct a missile against a target in a manner to cause the missile to strike the latter, and further having a popular appeal because it will provide a contest having competitive features suggestive of the game of baseball. A game apparatus of the kind toward the betterment of which the improvements of the instant invention are especially well adapted is exemplified by the disclosures of U. S. Patent No. 2,187,422, issued to me on January 16, 1940.

One principal object of the present invention is to provide a game apparatus of the class indicated above, which is novel and valuable in that it is of markedly simple and inexpensive nature.

Another principal object is to provide a game apparatus as aforesaid, and one so constructed and operating, that the missile employed may be an elongate one, such as a dart, and yet the provision is such that said missile, on striking the target-area defining opening, is able instantaneously to free itself from the target and target-area defining opening incidental to rebound of the said missile from the target after striking the latter. To insure such rebound, the dart employed may be the type of dart customarily used in any of the multitude of different dart-throwing games, but one from which the usual piercing spike is eliminated. According to the patent aforesaid, at the instant the missile despatched toward the target strikes the latter, there is substantially simultaneously set up a relative movement between the respective bounds of two openings both ahead of the target and mutually in registry at the instant the missile passes through both thereof on the last stage of its travel toward the target. This relative movement between oppositely facing edge portions of the said two openings is in a direction parallel to the plane of the target face. The result is that when a dart has heretofore been sought to be used as the missile to constitute the projectile object of play, there was a scissoring action as between the said two edge portions of the two openings, such that before the dart (with its spike eliminated) could rebound from the target for thereby effecting self-ejection from the game apparatus, said scissoring action occurred, and the dart would be transversely seized somewhere along its length tightly enough to entrap the same and the game's mechanism.

According to the instant invention, however, the arrangement is such at and adjacent to the target-area defining opening that the described scissoring action is made impossible under any circumstances; and indeed, while a target area defining opening is provided in a plane parallel with the plane of the target face, and this opening is given a movement past the target face substantially simultaneously with the striking of the target by a missile just previously travelling through said

2

opening, this movement of said opening relative to the target acts positively to assist the dart in its self-ejection from the game apparatus incidental to its rebound from the target immediately on striking the same.

Other objects, features and advantages of the instant invention will hereinbelow be pointed out or become obvious as the description proceeds.

In the accompanying drawing, wherein an illustrative embodiment of the invention is disclosed,

Fig. 1 is a front elevational view of a game constructed in accordance with the invention;

Fig. 2 is a side elevational view of the same;

Fig. 3 is a view of the rear of the game, showing the operating mechanism, and

Fig. 4 is a view looking at the mechanism of Fig. 3 from the left, with parts shown in section to more clearly disclose the structure.

Referring to the drawing, 4 indicates the playing field of the game, the same as here shown being substantially diamond shape to thereby represent a baseball diamond. It is provided with an indicium here shown as a tab-like extension 11, intended to represent a player in the role of a base runner; and so is located at what is self-evident as the home plate location, the said extension 11 being located at the position shown in Fig. 1 each time that a player begins play.

The playing field 4 is a rotary structure secured on a spindle 3 held in a suitable bearing carried by a suitable support, as one on or constituting the base member 1 of the game apparatus. As here shown, such base member may consist of a suitable sheet of stiff material, such as heavy cardboard, Masonite or metal, reinforced around its edges if necessary by a suitable frame 2.

Provided in the playing field 4 is a plurality of round apertures indicated respectively at 5, 6, 7 and 8. In the form shown, these apertures are graduated in diameter, from the larger aperture 5 to the smaller aperture 8, although if desired, the apertures may be all made of the same size, without departing from the spirit of the invention, although making the game easier to win.

At 10 is shown a plunger head constituting the target, the same being of circular shape and so located that at each halt in the 90° rotative movements of the playing field 4, one or the other of the apertures 5 to 8 inclusive will register with the disk-shaped plunger head 10. In Fig. 1 the largest of the apertures, or that shown at 5, is indicated as being in register with the plunger head 10.

Secured on the spindle 3 to the rear of the base board 1 is a ratchet member 15 provided with four teeth, each of which is indicated at 16. Each of these teeth represents a position of halt of the playing field. A torsional spring 12 encircles the spindle 3 and has one end attached to the spindle and its other end secured by a screw 13 or other fastening element to the top edge of a cross brace 14 located at the back of the base member 1.

The plunger head or disk 10 is fixed on one end of a shaft 9 which is axially slidable through the base member 1 and through the cross brace 14. A guide plate 17 is fastened to the rear of the cross brace 14 and the shaft 9 slides through said guide plate when a missile, such as a dart, enters through that one of the four apertures 5 to 8 which then lies opposite the target 10 to act as a target area defining means, and forcibly strikes the face of the disk-target 10.

Secured on the shaft 9 is a dog 18 which dog is normally held in the position shown in Fig. 3 and in which position it is in engagement with one of the teeth 16, by means of a spring 22 surrounding the shaft 9 and

located between the outer face of the base member 1 and the rear of the target-disk plunger 10. One end of a coil spring 19 is attached to a pin 20 projecting from the dog, and the opposite end of the spring 19 is attached to an eyelet 22a secured to and projecting from the cross brace 14 as clearly seen in Fig. 3. Said spring 19 tends to hold the dog 18 in contact with a stop pin 21 projecting from the guide plate 17.

From the foregoing, the operation of the game will be readily understood. The torsional spring is placed under tension by manually rotating the playing field 4 in a clockwise direction, as viewed in Fig. 1. When this is done by aid of the extension 11 as a rewind handle, the ratchet 15 is rotated, with the teeth 16 thereon easily moving past the dog 18, since the dog can pivot as required to permit of the passage of the teeth. Rewinding is halted at a point to cause the diamond-shaped field 4 to assume the position shown in Fig. 1, wherein the large aperture 5 will be relocated in registry with the target-disk 10 and the base runner designative extension 11 will be in a lowermost position as shown so as to suggest a batter at home plate. The player then stands off from the game board for a required distance and tosses a dart at the same, seeking to cause the dart to pass through the aperture 5 and strike against the plunger head 10. The dart employed for the purpose should be one having the usual spike eliminated from its blunt forward end.

If the player is fortunate enough to hit the target-disk 10 as exposed through the aperture 5, the disk 10 and its attached shaft 9 will be driven inwardly, as shown in dotted lines in Fig. 4, and since the dog 18 is carried by the shaft 9, the dog will likewise be moved inwardly and thus disengaged from the lowermost tooth 16 of the ratchet 15. This will free the ratchet, and under the torsion of the spring 12, the ratchet will turn a quarter turn in the direction of the arrow in Fig. 3, to bring the next tooth 16 in position to be engaged by the dog 18 as the dog is moved back to its former position by urge of the spring 22.

When the ratchet 15 is moved for a quarter turn as just described, it will rotate the playing field 4 through 90°. That is to say, the base runner indicating tab 11 will become located at the right hand corner of the diamond at the first base position. At the same time, the aperture 6 will now be positioned in registry with the target disk 10, and since the aperture 6 is smaller in diameter than the aperture 5 and also smaller than the target 10, it will be apparent that the target has become reduced in size, making it more difficult for the player to hit the target 10 and for the runner now on first base to be advanced to second base. When the player is successful in striking the now-reduced target 10, the playing field will again be rotated for a quarter turn, bringing the next smaller aperture 7 before the target-disk 10, and advancing the base runner from first base to second base. Again when the target is struck, the field will be rotated for a quarter turn to bring the smaller aperture 8 in front of the target, thus further reducing the effective size of the target area, but now with the base runner (the extension 11) "on third."

Variations and modifications are possible, and parts of the improvements may be used without others.

As will be noted, the sheet member constituting the playing field 4, by its own diamond shape, that is, by the mere totality of its bounding edges, graphically suggests the "infield" or playing diamond of a baseball field, whenever said sheet member is at rest and consequently when some one of its apertures 5, 6, 7 and 8 is in registry with the target 10. This result, moreover, is attained without having to paint in or otherwise add, on the front of either the sheet member 4 or the

base member 1, base-lines such as shown in the aforesaid Patent No. 2,187,422 to me.

In order to have the accompanying drawing as simple and at the same time as clear as possible, the placement 5 of the target 10 has been shown as unnecessarily upwardly-spaced from the location of the extension 11 of the sheet member 4 with the latter in game-starting position as in Fig. 1. However, with the aperture 5 lowered on the sheet member 4 with the latter in its last-named position sufficiently to bring the low point on the periphery of said opening at about the upper point of the triangular enclave of the extension 11 onto the front of the sheet member 4, and with the target 10 correspondingly lowered, and with the apertures 6, 15 7 and 8 each relocated to be registrable with the target 10, all four of the apertures 5, 6, 7 and 8 would be so close to the points of the diamond outline of the sheet member 4, as graphically to suggest, merely by their locations whenever said sheet member is at rest, the 20 four base points of a baseball field generally referred to as home plate, first base, second base and third base.

What I claim is:

1. In a game apparatus, a main support, a disk having a shaft axially movable through the support, spring 25 means for urging the disk away from the support for a limited distance, an intermittently rotated member rotatively mounted on the support and located in front of the disk, said rotary member having a diamond-shaped outline and provided with a plurality of openings each of which represents a base on said diamond, one or the other of said openings being adapted to register with the disk during each pause in the rotative movements of the diamond-shaped member, spring-actuated ratchet means for intermittently rotating said 30 diamond-shaped member, means carried by said shaft of the disk for normally restraining the ratchet means from rotating the diamond-shaped member, said means on the shaft being temporarily rendered ineffective to restrain the ratchet means from rotating the diamond-shaped 35 member each time that the disk is moved toward the support by a blow from a thrown missile entering through one of the openings and striking the disk said diamond-shaped member being at the extreme front of the game apparatus, the edge portion of the diamond-shaped 40 rotary member around the opening through which the missile thus passes being effective to provide a wiping action to aid in displacing the thrown missile from said opening.

2. In a game apparatus, a support, a target member 50 mounted on the support, a shaft on said target member slidably axially through the support, a spring for urging the target member forwardly and in a direction away from the support, a rotative sheet member having a diamond-shaped outline formed with spaced apertures 55 adapted to be positioned in sequence in registry with the target member whereby missiles thrown toward the target member can enter through the aperture thus registered therewith and strike the target member and move the same toward the support, spring-operated means for imparting a rotative movement to the diamond-shaped sheet member, said means being held inoperative while the target member is urged forwardly by the spring and rendered operative to rotate said sheet member for a given distance when the target member is moved toward 60 the support by a blow from a thrown missile, the target member having a marginal edge portion around each of its apertures to provide a wiping action against a missile that has passed through said aperture, to thereby eject the thrown missile from said opening said diamond-shaped sheet member being at the extreme front of the apparatus thus to be unimpededly out in the open thereby to adapt said missile to be manually thrown through the air without trajectory limitations thereon by structural 65 components of the apparatus.

3. In a game of the kind incorporating a target and means for yieldingly urging said target to a forward position and for permitting rearward movement of the target in recoil thereof from the impact of a missile striking thereagainst, said game also of the kind incorporating a target area defining means in the form of a rotatably-mounted sheet member having a plurality of openings and fractionally rotatable to move one of said openings from registry with the target and substitute another of said openings in registry with the target, said game also of the type incorporating spring means effective when wound to cause fractional rotation of said sheet member in response to such a recoil of the target, as a new article of manufacture a sheet member as aforesaid which is substantially diamond shape in outline and adapted to be pivotally mounted with the axis of such pivot at the center of the diamond, which has four apertures each adjacent one of the four corners of the diamond, and which at one corner of the diamond carries a projection for facilitating manual rewind of said spring by a turning of the sheet member in the direction opposite to that in which it turns when rotated by said spring, whereby, with said sheet member the extreme frontal structure of the game, said missile may be a thrown dart with a forward end which is spikeless

10

5 thus to make of an opening in the sheet member through which said dart enters at the end of a throw thereof a wiping ejector of the dart, and whereby, at the same time, said projection is always out in the open and so always in sight of a player of the game visually to indicate during rotation of said sheet member an advance of a gamepiece and so as also to be readily manually accessible from the front of the game to facilitate use thereof for rewinding the spring.
